(57) **CLAIM**

The ornamental design for a cleaning brush as shown and described.

DESCRIPTION

FIG. 1 is a front perspective view of a cleaning brush, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

In these drawings, the broken lines illustrate portions of the article, and form no part of the claimed design.

1 Claim, 5 Drawing Sheets
